UNITED STATES PATENT OFFICE.

CLARENCE S. STEWARD, OF CHATTANOOGA, TENNESSEE.

ELECTRIC HEATER.

1,104,572.

Specification of Letters Patent. Patented July 21, 1914.

Application filed April 3, 1914. Serial No. 828,360.

To all whom it may concern:

Be it known that I, CLARENCE S. STEWARD, a citizen of the United States, residing at Chattanooga, in the county of Hamilton and State of Tennessee, have invented certain new and useful Improvements in Electric Heaters; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in electric heaters and the object in view is to produce a device of this nature, comprising a plate of steatite or other material which is provided with a series of concentric slots formed in the upper surface thereof and chambered for the reception of independent heating coils, so arranged that separate currents may be passed through either or all of the coils at the same time according to the degree of heat desired.

More specifically, the present invention comprises an electric heater in which separate heating coils are provided, one contained within another in concentric slots, widened to form chambered portions for the reception of the wiring, and connection between the partitions intermediate the chambered portions being formed by boring holes from the periphery of the plate through the various chambers.

My invention is illustrated in the accompanying drawings, in which:

Figure 1 is a top plan view. Fig. 2 is an edge view, and Fig. 3 is a sectional view on line 3—3 of Fig. 1.

Reference now being had to the details of the drawings by letter, A designates a plate of steatite or other suitable material which is provided with a series of concentrically formed grooves B, B, the lower portions of which are widened to form chambers, and which are adapted to receive a heating coil D, which coil passes through registering ducts E, E formed in the partitions intermediate the concentric slots B. One end of the wire is connected to a terminal F and its other end is connected to a terminal G.

Other concentrically formed slots, designated by letter H, are surrounded by the slots B and each slot H is chambered for the

reception of the heating coil K, which passes through registering slots L formed in the partitions intermediate the slots H. One end of the coil K is fastened to a terminal S and its other end is fastened to a terminal S'.

By the provision of an electric heater made in accordance with my invention, it will be noted that coils are provided through which separate circuits may be passed accordingly as it may be desired to heat one coil of wiring or the other, the central coil K being provided for the purpose of heating receptacles of smaller diameter than the outer coil, or all coils together may be utilized when it is desired to obtain a greater degree of heat than could be obtained by the use of a single coil.

While in the drawings I have shown a unit constructed of two separate circuits, it will be understood that I do not confine myself to any number of circuits, as obviously any number may be used and arranged in any suitable manner within the heating plate.

By the peculiar arrangement forming the holes or ducts through the partitions in the slots, by simply boring a hole from the edge as shown, the cutting away of the partitions upon the top is avoided, thus leaving a smooth upper surface, the wiring being passed through holes and connected to the terminals in the manner shown. By this arrangement of heater, the bottom is imperforate excepting at the points where the terminals pass through, thus forming a smooth surface upon the bottom as well as the top and, by the provision of the intersecting slots, designated by letter W, means is provided to allow the various parts to expand and contract without likelihood of the surface of the plate checking or cracking.

What I claim to be new is:

1. An electric heater comprising a single piece of steatite or other suitable material having a series of concentrically formed slots in the upper surface thereof and which slots are widened to form chambers, said chambers communicating with each other through ducts formed in the walls thereof, terminals passing through apertures in the bottoms of the ducts, the other portions of the bottoms being imperforate, coiled wires mounted in said chambers and passing through said ducts in the walls, said coils connected to the terminals and designed to

receive separate circuits to regulate the degree of heat.

2. An electric heater comprising a single piece of steatite or other suitable material having a series of concentrically formed slots in the upper surface thereof and which slots are widened to form chambers, said chambers communicating with each other through ducts formed in the walls thereof, terminals passing through apertures in the bottoms of the ducts, the other portions of the bottoms being imperforate, coiled wires mounted in said chambers and passing

through said ducts in the walls, said coils connected to the terminals and designed to receive separate circuits to regulate the degree of heat, the top of the plate having intersecting grooves formed at right angles to each other in the tops of the walls intermediate the slots.

20

In testimony whereof I hereunto affix my signature in presence of two witnesses.

CLARENCE S. STEWARD.
